UNITED STATES PATENT OFFICE.

RUDOLPH H. MARTENS, OF COLFAX, WASHINGTON.

DESIGN FOR A DOOR-LATCH.

SPECIFICATION forming part of Design No. 28,540, dated May 3, 1898.

Application filed February 2, 1898. Serial No. 668,892. Term of patent 14 years.

To all whom it may concern:

Be it known that I, RUDOLPH H. MARTENS, a citizen of the United States, residing at Colfax, in the county of Whitman and State of Washington, have invented and produced a certain new and original Design for Door-Latches; and I do declare the following to be a full, clear, and exact description of the invention, such as will enable others skilled in the art to which it appertains to make and use the same.

My invention relates to a new and original design for door-latches; and it consists of a latch of the configuration shown in the accompanying drawings, in which—

Figure 1 is a perspective view of the latch, and Fig. 2 is an end view.

The leading feature of my design consists in a latch having parallel arms 1, the outer ends of which slant in opposite directions 20 and the inner ends of which terminate in a rounded bail 2, one of said arms having an upwardly-projecting rectangular apertured lug 3 and a downwardly-projecting rectangular apertured lug 4. 25

What I claim is—

The design for a door-latch, as herein shown and described.

In testimony whereof I hereunto affix my signature in presence of two witnesses.

RUDOLPH H. MARTENS.

Witnesses:

WILBUR S. YEARSLEY,
R. H. REID.
